UNITED STATES PATENT OFFICE.

EDWIN S. FLARSHEIM, OF CINCINNATI, OHIO, ASSIGNOR TO THE LIEBEL-FLARSHEIM COMPANY, OF CINCINNATI, OHIO, A CORPORATION OF OHIO.

DESIGN FOR A TIME-SWITCH CASING.

Application filed May 19, 1927. Serial No. 22 100. Term of patent 14 years.

To all whom it may concern:

Be it known that I, EDWIN S. FLARSHEIM, a citizen of the United States, residing at Cincinnati, in the county of Hamilton and State of Ohio, have invented a new, original, and ornamental Design for Time Switch Casing, of which the following is a specification, reference being had to the accompanying drawing, forming a part thereof.

I claim:

The ornamental design for a time switch casing, as shown.

EDWIN S. FLARSHEIM.
